UNITED STATES PATENT OFFICE

95,736

DESIGN FOR A SHOE

Jacob Fishman, Brooklyn, N. Y., assignor to
Scholnick Shoe Co., Jamaica Plain, Mass., a
corporation of Massachusetts

Application August 20, 1934, Serial No. 52,997

Term of patent 3½ years

To all whom it may concern:

Be it known that I, Jacob Fishman, a citizen of the United States, residing at Brooklyn, in the county of Kings and State of New York, have invented a new, original, and ornamental Design for a Shoe, of which the following is a specification, reference being had to the accompanying drawing, forming a part thereof, in which

Fig. 1 is a view in perspective of a shoe showing my new design; and

Fig. 2 is a similar view of the opposite side of the shoe shown in Fig. 1.

The ornamental effect of my design resides in a wide band starting from the rear end of the counter and running along the inside upper

edge of the shoe, thence transversely in position to cross the instep of the wearer and having a flaring end which overlaps a shorter and similar band running upwardly from the outside shank edge of the sole, both bands being ornamented throughout by a plurality of parallel lines of stitching and both being distinct from the material of the upper throughout their entire length.

I claim:

The ornamental design for a shoe substantially as shown and described.

In testimony whereof, I have affixed my signature hereto.

JACOB FISHMAN.
